(No Model.)

R. G. STONE.
SEMAPHORE.

No. 351,003.

Patented Oct. 19, 1886.

N. PETERS. Photo-Lithographer, Washington, D. C.

UNITED STATES PATENT OFFICE.

RODERICK G. STONE, OF BOSTON, GEORGIA.

SEMAPHORE.

SPECIFICATION forming part of Letters Patent No. 351,003, dated October 19, 1883.

Application filed June 8, 1886. Serial No. 204,552. (No model.)

To all whom it may concern:

Be it known that I, RODERICK G. STONE, of Boston, in the county of Thomas and State of Georgia, have invented certain new and useful 5 Improvements in Semaphores, of which the following is a specification, reference being had to the accompanying drawings, and to the letters of reference marked thereon.

The object of the invention is to provide a 10 day and night signal for use on railroads, which shall be efficient and simple in construction, and not liable to become disarranged by the action of rain, snow, ice, or other causes.

15 In the accompanying drawings, Figure 1 is a front view of my improved semaphore set to indicate "danger," or so that the train must be brought to a stop. Fig. 2 is a similar view, showing the semaphore set for "safety." Fig. 20 3 is a vertical transverse section on the line *x-x*. Fig. 4 is a perspective view of the upper portion of the invention, part of the casing being removed to show the interior construction.

Similar letters of reference indicate similar 25 parts in the respective figures.

This invention is designed to constitute both a visible and an audible signal, although the features which provide for the sound signal, preferably produced by the explosion of a tor- 30 pedo placed upon one rail of the track, may be omitted and the visible signal used alone.

A A' are vertical posts arranged over or in proximity to a railroad-track, having a cross-beam, A''. A casing, A'', is provided at the 35 upper part of the posts A A' and cross-beam A'' by a planking or sheathing, the central portion of which is left open at each side, at *b*, the spaces thus formed being those through which the signals are made visible to an ap- 40 proaching train. The space *b* is preferably situated directly over the track, which is indicated by C. The top of the casing A'' is closed by the cross-beam A'', its lower part being open, and within the casing the signal 45 proper (indicated by D) slides.

The signal proper preferably consists of a board divided into two lengths, one of which is painted red, or other color, to indicate danger, or convey whatever other idea may 50 be agreed on, in accordance with road regulations, the other half being preferably white, to indicate safety or other understood condition.

It is here supposed, however, that it is the object of the invention to indicate "danger" and "safety," and that when the red signal is exhibited at the space *b* the engineer of an approaching train is required to stop upon seeing the signal; but should the white signal be displayed he may pass the signal. The red portion of the board D is indicated by *d* and 55 the white portion by *e*. The board D is preferably provided at its upper side with sheaves *f*, which run upon a rod, *g*, extending from the vertical post A to that A', and immediately under the cross-beam A''. Rope sheaves or 60 pulleys are attached to the vertical posts A A', as shown at *h h' h'' h'''*. A cord or wire, *i*, attaches to one end of the board D, and, passing through the post A and over the sheave *h*, is provided with a weight, *k*. To the opposite 65 end of the board is attached a cord, *i'*, which passes through the post A' over the sheave *h''*, through the vertical pipe *l*, (attached to the post A'), under the sheave *h'''*, and through the pipe or box *m* to the signal station or tower. 70 The end of the board at which the weight is located is also provided at its lower edge with a cord, *i''*, which, passing over the sheave *h'*, attaches to the outer end of a lever, *n*, whose inner end is jointed or pivoted to the vertical 75 post A. The lever *n*, when the danger-signal is displayed at the opening *b*, is adapted to rest over one rail of the track, as shown in Fig. 1, the end of the lever being flattened and enlarged, so as to rest upon and cover a tor- 80 pedo secured to the rail in the usual manner. The two divisions *d e* of the board D are each provided with a lantern, *o*, hung within an opening cut in the board, each lantern showing a light of the color of its division of the 85 signal-board. The lanterns are adapted to be lifted out from the board by a rod provided with a suitable hook.

The operation of the invention is as follows: Supposing it is intended to stop an approaching train before it reaches the point at which the semaphore is located, the red square or flag is exhibited, and at night the red lantern is lighted. The engineer should, therefore, on seeing the red signal stop; but should he not 90 see it, on reaching the semaphore a wheel of the engine will tread upon the outer end of the lever *n*, which rests over one rail, thus exploding the torpedo under the lever and giving to 95 100

the engineer an audible intimation that he must stop. If "safety" is intended to be indicated, the white portion of the board D and its lantern are displayed at the open space b, the 5 weight k being drawn up. By the same movement the lever n is lifted, the parts being, therefore, brought to the position shown in Fig. 2. The construction is such that on releasing the cord i' the signal will be automatically adjusted to "danger."

It is not essential to my invention that the upper rod, g, and sheaves f be used in connection with the sliding signal-board, as any other means of guiding it may be used. Neither need 15 the board be constructed of wood, as it may be of tin, sheet-iron, or cloth, and be used with or without the lanterns. Neither is it essential to the invention that the torpedo adjustment should be used with the signal-board.

20 The casing A" may be of wood, tin, or sheet-iron. From the fact that the lower portion of the casing is open while the top is closed, it is evident that snow cannot collect or drift within the casing to interfere with the sliding movement of the signal-board, and that the operating parts are fully protected from rain, &c.

Having described my invention, I claim—

1. The vertical support, cross-beam, and casing, the latter having open spaces, as described, combined with a sliding semaphore or board having different divisions or colors adapted to be displayed at said spaces, substantially as set forth.

2. The vertical posts, cross-beam, and casing, the latter having spaces and being open at the bottom, as described, combined with a semaphore or board having different divisions or colors to be displayed at said spaces, and adapted to slide within and be protected by 40 the casing, substantially as set forth.

3. The vertical posts, cross-beam, and casing, the latter having spaces, as described, combined with a cross-rod, and a semaphore or board having sheaves resting upon said rod and adapted to slide within said casing, said 45 semaphore or board having different divisions or colors to be displayed at said spaces, substantially as set forth.

4. The vertical posts, cross-beam, and casing, the latter having spaces, as described, 50 combined with a cross-rod, a semaphore or board having sheaves and adapted to slide on said rod, and cords, sheaves, and a weight for operating said board, said semaphore or board having different divisions or colors to be displayed at said spaces, substantially as set forth.

5. The combination of vertical posts, cross-beam, casing having spaces, as described, sliding semaphore or board, and lanterns, said semaphore or board having different divisions or 60 colors to be displayed at said spaces, substantially as set forth.

6. The vertical support, cross-beam, and casing, the latter having open spaces, as described, combined with a sliding semaphore 65 or board having different divisions or colors adapted to be displayed at said spaces, and with a lever arranged to rest over one rail of the track, and a connection between it and the semaphore, substantially as set forth.

In testimony whereof I hereunto set my hand and seal.

RODERICK G. STONE. [L. S.]
